UNITED STATES PATENT OFFICE.

EUGÈNE MOULIÉ, OF JACKSONVILLE, FLORIDA.

APPARATUS FOR RECEIVING, SEPARATING, AND FILTERING OILS.

1,075,265.

Specification of Letters Patent.

Patented Oct. 7, 1913.

Application filed January 25, 1913. Serial No. 744,149.

To all whom it may concern:

Be it known that I, EUGÈNE MOULIÉ, a citizen of the United States, and a resident of Jacksonville, in the county of Duval and State of Florida, have invented a new and Improved Apparatus for Receiving, Separating, and Filtering Oils, of which the following is a full, clear, and exact description.

My invention has for its object to provide an apparatus for receiving, separating and filtering the distillate of volatile and essential oils of all kinds, including spirits of turpentine and oils heavier than water. The apparatus also serves for purifying, separating and filtering all kinds of fixed oils. As the apparatus is constructed, it operates automatically, after it has been started and regulated.

In using the apparatus, as the distillate begins to run into the receiver, the only thing the operator need do is to regulate the exit flow so that the water and oil will separate automatically, each one going into its respective receiver.

Additional objects of the invention will appear in the following complete specification, in which the preferred form of the invention is disclosed.

In the drawings similar characters of reference indicate corresponding parts in both the views, in which—

Figure 1 is an elevation of my apparatus, connected with a still and condenser, with parts broken away to show the construction; and Fig. 2 is an enlarged sectional elevation showing how the lower terminal of the receiving tube extends upward in the separating tube.

By referring to the drawings it will be seen that a still 5 is provided, which is connected in the usual manner with a condenser 6, this condenser 6 having an outlet 7 above the funnel 9 of the pipe 8, the pipe 8 connecting the outlet 7 with the receiving tube, 10. This receiving tube 10, which is preferably of glass, is provided with a lower terminal 11, constructed of copper, inside and out. This lower terminal 11 is integral with the section 12 of the separating tube 13. The lower end 11 of the receiving tube 10 has an upwardly extending terminal 14, disposed in the section 12 of the separating tube 13, and extending upwardly in the section 15 of the separating tube 13, this section 15 being preferably constructed of glass. The receiving tube 10 is connected

with the lower end 11 of the receiving tube by a rubber coupling member 16, and the section 15 of the separating tube 13 is connected with the section 12 of the separating tube by a similar rubber coupling member 17. The section 12 of the separating tube is not only connected with the section 15, but also with a separating tube section 18, which is disposed below the section 12, and which is connected with the section 12 by the rubber coupling member 19. This section 18 is connected with a section 20 of the separating tube by means of a rubber coupling member 21. The outlet tube 33, a gage 37, the separating tube 13 and the receiving tube 10 are connected by a wire 43 as shown in the drawings, which serves as a support.

As will be seen by referring to Fig. 1 of the drawings, the section 20 has an enlarged portion 22, forming a separating chamber 23, the sides of the section 20 of the separating tube converging below this chamber 23, the section 20 connecting with the outlet 24 and with the conduit 25. The outlet 24 is normally closed by means of a cork 26, which is disposed in the outer end of the said outlet. The lower end 11 of the receiving tube 10 has an outlet 27, disposed adjacent the separating tube 13, this outlet 27 being normally closed by means of a cork 28. At the top of the separating tube 15, there is a horizontal outlet 29 connected with the section 15 of the separating tube by means of a rubber coupling 30, this horizontal outlet 29 having a depending lip 31, which prevents the oil leaving the outlet from running down the outer side of the outlet. The conduit 25, which is commanded by a valve 32 leads to a vertical outlet tube 33, this outlet tube 33 having a plurality of outlets 34, which are spaced apart at different heights, a horizontal outlet member 35 being provided, which may be connected with any one of the outlets 34, by means of the rubber coupling member 36. The regulation of the flow of the distillates, both water and oil, is accomplished with the valve 32, this valve 32 checking and regulating the flow between the separating tube 13 below the chamber 23 and the outlet tube. There is also connected with this conduit 25 a gage 37, which is commanded by a valve 38. As my device is constructed it can dispose of the distillates from a charge of materials, flowers, leaves, barks, roots, skins, etc., from five pounds to three hun-

dred pounds, and it can be constructed of any desired proportions, for receiving a large charge.

The still 5 and the condenser 6 are operated in the customary manner, and as the distillate water and oil fall from the condenser to the receiving tube 10, they flow downward to the lower end 11 of the receiving tube 10, and then upward and out of the terminal 14 in the separating tube. The oil is partially separated from the water as it leaves the terminal 14, the water and the oil then flowing downward in the separating tube, the oil separating completely from the water when they reach the chamber 23, where the surface space is large enough to cause the oil to spread, and then take an upward course while the water runs down to the bottom, but does not flow through the conduit 25, as the valve 32 has been previously closed.

In most cases it is advisable to permit several ounces of the first flow from the condenser to run through the outlet 24, this first flow from the condenser carrying some impurities that may be gathered from the condenser. This first flow from the condenser is obtained from the outlet 24 by removing the cork 26, after which the cork 26 is replaced. The distillate, after it has been obtained through the outlet 24, is poured in the still, through the inlet 38, the cap 39 having been previously removed.

The function of the upturned terminal 14 which discharges this distillate into the separating tube 13 is to check the pressure of the flow through the receiving tube 10, and to accomplish the partial separation of the distillates so that the oil which is carried down by the pressure in the form of large globules, on account of the narrow space in the tube, may easily separate from the water, on or before leaving the chamber 23 of the separating tube 13. The oil never falls lower than said chamber 23. When the distillates reach the level of the outlet 34^a, of the outlet tube 33, the valve 32 is partially opened, so that the water distillate can run into the gage 37, and into the outlet tube 33.

As the operation proceeds by the aid of the valve 32, the running of the water into the outlet tube 33, and the gage 37, is regulated, and when the top outlet 34^b is reached, which is indicated on the gage 37, the water is permitted to flow through the horizontal outlet member 35, and may be caught in any suitable receiver. At this stage of the operation the top level of the oil has, of course, reached the level of the outlet 34^b, and accumulated downward below that level, and when that accumulation has reached the terminal 14, the running of the water is slightly checked by the aid of the valve 32, and this will raise the level in the receiving tube 10 and the outlet tube 33, which will

raise the level of the oil in the separating tube 13 and will cause the oil to flow out of the horizontal outlet 29, the oil falling into the funnel 40, provided with a filter, and disposed over the receptacle 41, this receptacle 41 being mounted on a box 42, which supports the separating tube 13. When the oil commences to flow from the horizontal outlet 29, the flow of the distillate from the horizontal outlet 35 may be regulated by the valve 32, so that the apparatus will work automatically, without it being necessary for the operator to give the apparatus further attention other than to have suitable receptacles for receiving the oil and the water distillate. When the still 5 is no longer in operation, and the distillate no longer flows from the condenser 6, it is necessary to gather the remaining distillates, oil and water, in the apparatus, and as in many cases the oil is of considerable value, it is necessary that the oil be separated from the water distillate, and be gathered to the last drop. At this stage the distillates, the oil on top, in the receiving tube 10 and in the separating tube 13, are substantially at the level of the horizontal outlet 35, and there may be several inches of oil in the receiving tube 10 and the separating tube 13. In order to force the oil out through the horizontal outlet 29, water distillate is poured very slowly into the gage 37, at its top. This will gradually force the oil to run out of the horizontal outlet 29 into the filtering funnel 40. When only some drops of oil are left, in the receiving tube 10, and the separating tube 13, the pouring of the water distillate in the gage 37 is discontinued. Then the outlet 34^c of the outlet tube 33 is opened, and the water distillate is run off until the level of that outlet is reached. The outlet 34^c is then closed, with its cork 34^d, but after this has been done there still remains in the member 11 and the terminal 14 some distillates, which have to be taken out and to accomplish this these tubes are drained by opening the outlet 27, the contents, which are water and oil, being received into a narrow bottle.

The two rubber coupling members 17 and 19 are then removed which enables the taking away of the section 15 of the separating tube 13, with its outlet tube 29, the section 12 of the separating tube 13, and the receiving tube 10 being also removed. This leaves attached to the apparatus the section 18 of the separating tube, in which the contents of the narrow bottle are carefully poured, and left to settle, until the oil has separated and floats at the surface of the water. When the separation is complete the horizontal outlet 29 is disconnected from the section 15 of the separating tube 13, and adjusted with a rubber coupling to the top of the section 18 of the separating tube, in which are the distillates.

After having arranged a filtering funnel under the lip 31 of the horizontal outlet 29, and a receptacle under the filtering funnel 40, water distillate is again poured drop by drop into the gage 37, and the last drop may in this manner be forced out through the outlet 29. However, as a precaution, it is sometimes advisable to remove the outlet 29, and to gather the last drops of oil with 5 a pipette. When a material differing from the one previously used is to be distilled, the apparatus must be thoroughly cleaned. This is done with alcohol, and the alcohol is subsequently drained out through the lowest outlet 24. It should be noted that the outlets 10 29 and 35 are horizontal, so that there will be no possibility of these outlets operating in connection with the tubes as siphons.

The operation with essential oils heavier 20 than water differs from the operation with volatile oils. The apparatus is mounted in the same way, but the valves 38 and 32 are closed, and while the distillates run out from the condenser, none can run through 25 the conduit 25 as the valve 32 is closed, and consequently the distillates remain in the separating tube 13, the water being on top. When the water runs out from the horizontal outlet 29, and the level of the oil in 30 the separating tube reaches the level of the outlet 34^b, of the outlet tube 33, the bottom outlet 34 of the outlet tube 33 is opened, and also gradually the valve 32, so that the oil can run out from the bottom outlet 34, 35 of the outlet tube 33, into the filtering funnel, and into the oil receiver suitably placed. The running of the oil is regulated so that the level of the oil in the separating tube is kept at about the level of the outlet 34^c of 40 the outlet tube 33. In this way the apparatus is regulated, until the end of the distillation, when the valve 32 and the lower outlet 34 are closed, and, in order to collect 45 the oil left in the receiving and separating tubes the water is first forced out by pouring some of the oil, drop by drop, if need be, into the receiving tube 10, this being continued until the oil reaches the rubber coupling 30. The lower outlet 34 in the outlet 50 tube 33, and also the valve 32, are opened again, and the oil permitted to run out until its level has come down to the level of the outlet 34^c then the valve 32 is again closed, and any oil which may still be in the 55 conduit 25 between the valve 32 and the lower outlet 34, of the outlet tube 33, is permitted to flow out through the lower outlet 34, by slightly inclining the apparatus, after which the lower outlet 34 is 60 closed, as well as the valve 32. When this has been done, the outlet 27 is opened, and the contents received into a narrow bottle, and when the draining is completed, the member 11 is disconnected from the separating 65 tube. The filtering funnel is then placed

under the outlet 24, and some oil allowed to run out into a receiver, to make sufficient room in the separating tube to receive the contents of the narrow bottle, which are poured into the separating tube, and as 70 there is very little water in the separating tube it may be easily taken out by a pipette, after which the outlet 24 is again opened, and the oil drained entirely.

In addition to the uses described above, 75 the apparatus may be used for separating and filtering fixed oils. When the fixed oils coming from the press are required to be purified, because of the mucilage which may be held in suspension, this purification 80 is generally accomplished with boiling water, this water being acidulated according to circumstances. My apparatus may then be used to separate the oil from the water, and filter the oil on the same principles as for the separation of the distillates of volatile oils, and with the same savings, and perfect results. The construction of 85 the separating tube which is narrow in proportion to the size of the apparatus is important, as with it the surface of the oil on top of the water has a very small area. This reduces to a minimum the loss caused by adhesion of the oil to the inner walls of 90 the separating tube.

Having thus described my invention, I claim as new, and desire to secure by Letters Patent:

1. An apparatus of the class described, a separating tube having an opening, a receiving tube having a terminal extending through the opening, and upward in the separating tube, the separating tube having a horizontally disposed terminal above the opening, outlet means connected with the 100 separating tube below the opening therein, and an outlet for the receiving tube adjacent the separating tube.

2. In an apparatus of the class described, a vertical separating tube having an enlarged portion forming a chamber intermediate of its terminals, a receiving tube opening into the interior of the separating tube, and having a terminal extending upwardly in the separating tube, a horizontal outlet 110 for the top of the separating tube, and an outlet for the receiving tube adjacent the separating tube.

3. In an apparatus of the class described, a vertical separating tube having an enlarged portion forming a chamber intermediate of its terminal, a receiving tube opening into the interior of the separating tube above the chamber, a vertical tube connected with the bottom of the separating tube, and 120 having a plurality of outlets disposed at different levels.

4. In an apparatus of the class described, a vertical separating tube having an enlarged portion forming a chamber interne- 130

diate of its terminals, a receiving tube opening into the interior of the separating tube above the chamber, a vertical tube connected with the bottom of the separating tube, and having a plurality of outlets disposed at different levels, and a valve for cutting off communication between the separating tube and the third tube.

5. In an apparatus of the class described, 10 a vertical separating tube having an enlarged portion forming a chamber intermediate of its terminals, a receiving tube opening into the interior of the separating tube, and having a terminal extending upwardly 15 in the separating tube, and a vertical tube connected with the bottom of the separating tube and having a plurality of outlets at different levels.

6. In an apparatus of the class described, 20 a separating tube having an opening, a receiving tube having a terminal extending through the opening, and upward in the separating tube, the separating tube having a horizontally disposed terminal above the 25 opening, outlet means connected with the separating tube below the opening therein, a vertical tube connected with the bottom of the separating tube, and having a plurality of outlets at different levels, and a valve for 30 regulating communication between the separating tube and the third tube.

7. In an apparatus of the class described, 35 a separating tube having an opening, a receiving tube having a terminal extending through the opening, and upward in the separating tube, the separating tube having a horizontally disposed terminal above the opening, outlet means connected with the separating tube below the opening therein, a 40 vertical tube connected with the bottom of the separating tube, and having a plurality of outlets at different levels, a valve for regulating communication between the separating tube and the third tube, and an outlet 45 for the receiving tube, adjacent the separating tube.

8. In an apparatus of the class described, 50 a vertical separating tube with a lateral opening and having a horizontal outlet at its upper end, and a receiving tube having communication with the separating tube through the opening, a vertical tube having communication with the separating tube below the opening, and provided with a plurality of 55 outlets at different levels, and a valve for regulating communication between the separating tube and the third tube.

9. In an apparatus of the class described, 60 a vertical separating tube with a lateral opening, provided with an enlarged portion therebelow, forming a chamber, the vertical separating tube having a horizontal outlet at its upper end, and a receiving tube having communication with the separating tube 65 through the opening, a vertical tube having

communication with the separating tube below the opening, and provided with a plurality of outlets at different levels, and a valve for regulating communication between the separating tube and the third tube.

10. In an apparatus of the class described, 70 a vertical separating tube with a lateral opening, and having a horizontal outlet at its upper end, a receiving tube having communication with the separating tube through the opening, and provided with a terminal 75 extending upward in the separating tube, a vertical tube having communication with the separating tube below the opening, and provided with a plurality of outlets at different levels, and a valve for regulating communication between the separating tube and the third tube.

11. In an apparatus of the class described, 80 a vertical separating tube with a lateral opening, and an enlarged portion therebelow forming a chamber, a horizontal outlet for the upper end of the separating tube, a receiving tube having communication with the separating tube through the opening, 85 and provided with a terminal extending upward in the separating tube, a vertical tube having communication with the separating tube below the opening, and provided with a plurality of outlets at different levels, and a valve for regulating communication between the separating tube and the third tube.

12. In an apparatus of the class described, 90 a vertical separating tube with a lateral opening and having a horizontal outlet at its upper end, and a receiving tube having communication with the separating tube through the opening, a vertical tube having communication with the separating tube below the opening, and provided with a plurality of outlets at different levels, a valve for regulating communication between the separating tube and the third tube, the lower 95 end of the separating tube being provided with an outlet.

13. In an apparatus of the class described, 100 a vertical separating tube with a lateral opening, and an enlarged portion therebelow forming a chamber, a horizontal outlet for the upper end of the separating tube, a receiving tube having communication with the separating tube through the opening, and provided with a terminal extending upward in the separating tube, a vertical tube 105 having communication with the separating tube below the opening, and provided with a plurality of outlets at different levels, a valve for regulating communication between the separating tube and the third tube, the lower end of the separating tube being provided 110 with an outlet.

14. In an apparatus of the class described, 115 a vertical separating tube having an enlarged portion forming a chamber, interme- 120

diate of its terminals, a receiving tube opening into the interior of the separating tube and having a terminal extending upwardly in the separating tube, a vertical outlet tube, communicating means connecting the separating tube below its enlarged portion with the outlet tube, and a valve in the communicating means for regulating the flow of liquid from the separating tube to the outlet tube.

15. In an apparatus of the class described, a vertical separating tube, a receiving tube opening into the interior of the separating tube and having a terminal extending upwardly in the separating tube, a vertical

outlet tube, communicating means connecting the bottom of the separating tube with the bottom of the outlet tube, and a valve in the communicating means for regulating the flow of fluid from the separating tube to 20 the outlet tube.

In testimony whereof I have signed my name to this specification in the presence of two subscribing witnesses.

EUGÈNE MOULIÉ.
